UNITED STATES PATENT OFFICE.

JAMES S. PENNEFATHER, OF NEW YORK, N. Y., ASSIGNOR OF ONE-HALF TO WILLIAM E. PRICE, OF NEW YORK, N. Y.

LAMP-FIXTURE.

1,351,681.

Specification of Letters Patent. Patented Aug. 31, 1920.

Application filed July 30, 1919. Serial No. 314,209.

To all whom it may concern:

Be it known that I, JAMES S. PENNEFATHER, a citizen of the United States, and a resident of the city of New York, in the 5 county of New York and State of New York, have invented a new and Improved Lamp-Fixture, of which the following is a full, clear, and exact description.

This invention relates to improvements in 10 lamp fixtures, and more particularly to an adapter or fixture used for the purpose of converting a vase into a base for supporting an electric light and shade fixture.

An object of the invention is to provide 15 an adjustable adapter to fit various forms, shapes, sizes, and heights of vases in order to make the vase support an electric light. The device herein described provides a portable electric lamp which will find ready and 20 convenient use in the household and other places.

It is a particular object to provide an adjustable fixture simple in design and construction and which may be readily mounted 25 upon a vase, and which will be ornamental in appearance.

With the above principal objects and others in view the invention has relation to 30 a combination of parts to form a vase attachment for electric light, an example of which is presented in the following specification, pointed out in the appended claims, and portrayed in the accompanying drawings, wherein;

35 Figure 1 illustrates a vase provided with the attachment fixture and supporting an electric light and shade.

Fig. 2 illustrates a plan view of the vase with the vase cover removed in order to 40 close the adjustable attachment arms.

Fig. 3 illustrates a vertical sectional view as taken on the sectional line 3—3 of Fig. 2.

Fig. 4 shows a cover employed to conceal the attachment arms of the fixture, and Fig. 45 5 is a sectional view taken on the line 5—5 of Fig. 4.

Fig. 6 illustrates the attachment fixture applied to a form of vase slightly varying in 50 design from the vase shown in Figs. 1, 2, and 3. This vase is presented to show how the attachment fixture is universal in application to several different designs of vases.

Fig. 7 illustrates a side elevation of a sectional cover or cap employed to conceal the

attachment fixture and to close the vase; 55 and Fig. 8 shows a plan view of Fig. 7.

Fig. 9 illustrates one section of the cover shown in Figs. 7 and 8 applied to a vase.

An electric light fixture or attachment for mounting a light and shade on a vase 60 built according to the plans of my invention, consists of a vertical support adjustable in length and provided with attachment arms to engage the rim or lip of a vase. A cover is employed and a light may 65 be mounted on the top of the vertical support.

Referring more particularly to the drawings for a detailed description of this invention, the reference numeral 10 designates 70 a tubular support provided with a telescoping rod 11. The lower end of the rod is fitted with an anchor base 12 which rests in the bottom of the vase, and to securely hold the parts in steady position a quantity of 75 sand or other heavy material may be poured into the vase and packed against the anchor base 12 and rod 11. The tubular support is provided with a set screw 14 in order that the members 10 and 11 may be properly adjusted in length and fixed one upon the other to form a substantial and immovable structure.

A hub 15 provided with a plurality of radial arms 16, is disposed upon the vertical 85 support tube 10. The hub 15 is provided with a set screw 17. The set screw is set up against the tube 10 to hold the hub and arm members in fixed position upon said tube. Each radial arm is fitted with an extensible 90 clamp arm 18, and a hook 19 is provided on the outer end of each extensible arm. Each extensible member 18 is provided with a slot 20, and a screw 21 is inserted through each slot 20 and threaded into the radial arm 16. 95 The screw 21 is set up against the extensible arm 18 to hold it in fixed relation with radial arm 16. The outer hooks 19 are arranged to over-hang the rim or lip of the vase, and then the set screws 21 are screwed tightly 100 against the members to hold all parts in rigid position. The radial arms with the extensible members may be adjusted to vases of varying diameters and thus made to support the tube or staff 10 in a vertical and 105 substantial position.

A metal cover 22 is employed to conceal the attachment arms with associated parts,

and to close the vase. This cover may be made in one or two parts as disclosed in the drawings. Figs. 7 and 8 illustrate a two-part sectional cover cap employed to 5 close the vase and conceal the parts of the fixture. The two-part cover cap is constructed of thin sheet metal, and threaded hub 23 formed thereon. The cover may be mounted on the member 10 and clamped by 10 a nut 24 firmly screwed down on the threaded hub. This construction is brought out in the Figs. 7, 8, and 9 where the numeral 25 points out the two sections of a complete cover. The edges over-lap slightly in order 15 to form a closed joint. The cover is provided with a hole therein and a ferrule 25^a through which a flexible lamp cord may be passed in order to connect the fixture with an electric light extension or ceiling light. 20 Fig. 1 shows a completed electric lamp fixture constructed along the lines herein disclosed. A vase 30 and any suitable electric light shade 31 has been employed in connection with the described attachment 25 fixtures and the resulting combination presents a unique and ornamental electric light fixture. The flexible lamp cord 32 is passed out through the cover. No damage whatsoever accrues to a vase however valuable 30 when used as a base or support for an electric light when constructed according to the plans of this invention. The electric light globes and accessory fixtures 33 are installed in any appropriate way on the upper extremity of the staff 10.

Fig. 6 shows a type of vase 34 somewhat different in design to the vase shown in the other figures of the drawing. In the vase 34 the upper rim turns inwardly rather than 40 outwardly. This invention takes into consideration the various designs of the vases and presents means for universally adapting the attachment fixtures to the several designs of vases and particularly to the several designs of lips or rims of vases. The 45 extensible arms 18 are also provided with hooks 19^a. These hooks are disposed oppositely from the hooks 19, in other words the extensible arm member 18 is provided 50 on each end thereof with the oppositely disposed hook 19^a. In applying the attachment fixture to a vase with an out-turned rim such as shown in Fig. 3, the inwardly turned hooks 19 are necessarily used; while the 55 hooks 19^a will better fit an inwardly turned rim of a vase such as shown in Fig. 6. The change is made by loosening the set screws and reversing the extensible arms.

This form of attachment fixture provides 60 a simple, inexpensive, and ready means for converting a vase into an electric light fix-

ture. It provides an ornamental lamp of household utility, beauty, and value.

Having thus described my invention, I hereby claim as new and desire to secure by 65 Letters Patent as follows:

1. An attachment for converting vases into electric lamp fixtures, comprising; a tubular staff, a rod telescopingly inserted therein, means for fixing the tubular staff and rod rigidly one with the other, a base made on the lower end of the rod to fit in the bottom of a vase, a hub slidably mounted on the tubular shade staff, a plurality of radial arms integrally formed with the hub, 75 an extensible arm member fixed and adjustably associated with each radial arm, an inwardly down-turned hook formed on one end of the extensible arm, and an up-turned outwardly directed hook member formed on the other end of an extensible arm adapting 80 the device to attachment with various designs of vase rims.

2. An attachment for converting vases into electric lamp fixtures, comprising; a 85 tubular staff, a rod telescopingly inserted therein, means for fixing the tubular shade staff and rod rigidly one with the other, a base made on the lower end of the rod to fit in the bottom of a vase, a hub slidably 90 mounted on the tubular staff, a plurality of radial arms integrally formed with the hub, an extensible arm adjustably associated with each radial arm, an inwardly down-turned hook formed on one end of the extensible arm, and an up-turned outwardly directed hook formed on the other end of the extensible arm adapting the device to attachment with various designs of vase 95 rims, and a cover cap employed to close the 100 vase and cover the parts named.

3. An adapter for securing illuminating fixtures to vases, comprising; a rod inserted in a vase, an anchor base carried on the end of the rod to mount said rod in the 105 vase, a hub on the rod, radial arms on the hub, a clamp arm adjustably related with each radial arm, and a hook made on each end of the clamp arm to grasp the rim of a vase.

4. An adapter for securing illuminating fixtures to vases, comprising; a rod inserted in a vase, an anchor base carried on the end of the rod to mount said rod in the vase, a hub on the rod, radial arms on the hub, a 115 clamp arm adjustably related with each radial arm, a hook made on each end of the clamp arm to grasp the rim of a vase, and a cover plate mounted on the vase to conceal the parts comprising the adapter.

JAMES S. PENNEFATHER.
